CLAIM

The ornamental design for a medication case, as shown and described.

DESCRIPTION

FIG. 1 is a top and left side perspective view of a medication case showing the new design;

FIG. 2 is a bottom and right side perspective view of the medication case;

FIG. 3 is a front view of the medication case;

FIG. 4 is a rear view of the medication case;

FIG. 5 is a left side view of the medication case;

FIG. 6 is a right side view of the medication case;

FIG. 7 is a top view of the medication case;

FIG. 8 is a bottom view of the medication case;

FIG. 9 is an enlarged view of the portion surrounded by the dash-dot line in FIG. 2; and,

FIG. 10 is a top and left side perspective view of the medication case in its open state.

The dash-dot broken line in FIG. 2 and FIG. 9 represents the boundary of the enlarged partial view and forms no part of the claimed design.

The broken lines in the drawings depict portions of the medication case that form no part of the claimed design. The interior part of the medication case in its open state forms no part of the claimed design. In FIG. 10, the claimed surface of the medication case ends at where the solid line details end.
